SEPARATOR

Frank Young Hutchison, Houston, Tex., assignor
to Houston Pipe Line Company, Houston, Tex.,
a corporation of Texas

Application July 6, 1938, Serial No. 217,771

1 Claim. (Cl. 183—2.7)

This invention relates generally to separators, and more particularly to separators designed to remove liquid or heavy particles of gas from gaseous vapors.

5 The main object of the invention is to provide a separator of the character referred to which is positively automatic in its operation, and of such simple construction as to involve the use of a minimum number of parts.

10 Other objects of the invention will become apparent as the detailed description thereof proceeds.

In the drawing:

Figure 1 is a central, vertical section through the separator taken substantially on the line 1—1 of Figure 2;

Figure 2 is a top plan view of the separator with parts thereof broken away and shown in sections to illustrate details of construction;

20 Figure 3 is a vertical, transverse section taken on the line 3—3 of Figure 1; and

Figure 4 is a fragmentary cross section, to an enlarged scale, of the adsorption element of the separator.

25 Referring now to the drawing in which like reference numerals refer to the same parts in the several figures thereof, the separator comprises an inlet pipe 5 adapted to be connected to a source of supply of the gas or vapor to be

30 separated. This pipe 5 extends radially through the side of a drum 6 of comparatively large diameter, and is connected to the center of a pipe 7 which is suitably supported within the drum 6 and coaxially therewith. In the normal

35 operation of the separator, the drum 6 and pipe 7 are supported in substantially horizontal position, the pipe 7 being provided in its lower part with a slot 8 extending throughout the length of the said pipe to effect discharge of gas into

40 the drum 6, as a thin ribbon of gas having substantially the same width as the length of the pipe 7.

By spreading the gas entering at relatively high velocity, the gas strikes against the inner sur-

45 face of the drum 6, and its velocity is reduced considerably because of the large increase in cross sectional area in the drum with respect to that of pipe 7 transversely of the direction of flow of the ribbon of gas. This spreading of the

50 gas into a thin, wide ribbon assures that every portion of the gas will have intimate impact upon the metal wall of the drum 6. The inertia of the heavier liquid particles in the gas forces them into intimate contact with this metallic

55 surface, and with the immediate absence of any

force to renew their movement in another direction, the particles tend to collect in the lower part of the drum 6 whence they may be carried off by gravity.

The gas, from which the liquid particles aforesaid have been separated, is conducted by a series of conduits 9 to an adsorption drum 10 connected to an outlet system of piping 11. The conduits 9 are connected at one of their ends to the upper surface of the drum 6, and are curved so that their other ends extend substantially horizontal for connection to one side of the adsorption drum 10. While there are three of such conduits illustrated in the drawing, the invention is not limited to any particular number, since all that is necessary in this connection is to provide the drum with conducting means large enough to transport the gas efficiently from one drum to another.

To carry off the separated liquids, the drum 6 is connected by a series of down pipes 12 to a collecting drum 13 substantially parallel with the drum 6. The drum 10 is also connected by a series of down pipes 13' to a collecting drum 14 arranged substantially parallel to the drum 10. The drums 13 and 14 are provided with bull plugs 15 and 16 connected to each other by a pipe 17. Condensation from the drums 13 and 14 is removed therefrom through the pipe 17 by the steam trap designated generally by the reference numeral 18. A choke 19, mounted in the pipe 17 adjacent the bull plug 16, prevents the by-passing of gas downwardly through the lower drum and thence upwardly to the exit piping 11.

35 The adsorption drum 10 is provided with a foraminous plate 20 extending substantially vertical throughout the length of the drum and located between the axis of the drum and the gas exit formed by the piping 11. A second 40 foraminous plate 21, inclined to the vertical, is mounted in the drum 10 and extends substantially throughout the length thereof across the inlet end of the transverse conduits 9. The lower edge of the plate 21 lies substantially in 45 the plane of the axis of the drum 10 and the axes of the down pipes 13' to provide passageways 22 for the particles which fall by gravity through the down pipes 13'. The lower edge of the plate 21 is also provided with apertured 50 flanges 23 which fit into the apertures formed in the drum 6 for the purpose of receiving the upper ends of the down pipes 13'.

The foraminous plates 20 and 21 form the side walls of an adsorption chamber adapted to hold 55

broken brick or other material forming a rough and porous mass through the interstices of which the low velocity gas may pass to the outlet piping 11.

5 In the operation of this separator, which is primarily designed for use in oil and gas development, the gas entering the inlet pipe 5 at high velocity impinges against the inner surface of the transverse pipe 7 and spreads lengthwise of 10 that pipe to be discharged as a thin ribbon of gas downwardly through the slot 8. The velocity of the gas is materially reduced because of the great increase in cross sectional area of the gas conduit formed by the drum 6. The thin ribbon 15 flow assures that every portion of the gas will have intimate impact upon the metal wall of the drum 6. The inertia of the heavier liquid particles in the gas forces them into intimate contact with the surface of said wall; consequently, 20 in the absence of any force to renew their movement in another direction, the liquid particles tend to collect and are carried by gravity through the down pipes 12 into the lower collecting drum 13. The slugs of liquid formed in the drum 6 25 are thus directed to the lower drums 13; and because of the decrease in velocity of the gas through the drum 6 there is no tendency to entrain any of these liquid particles and carry them further. It will be observed that as wet gas enters 30 the distributing pipe 7, velocity is immediately reduced. In the particular form shown, in which gas inlet pipe 5 communicates with an intermediate portion of distributing pipe 7, inflowing gas immediately may expand in opposite directions toward the ends of the pipe 7 and thus more effectively diminish velocity than as if the gas entered at one end of pipe 7. Then, as this retarded gas issues from the longitudinal slot 8 into the drum 6, a considerable expansion 35 of the gas ensues at once. The liquid particles immediately impinge against the opposing wall of drum 6 which extends opposite and substantially parallel to the slot. This abruptly terminates the travel of the liquid particles and collects them for continual removal from the drum 40 6. As shown, for example, in Figure 1, the wall of drum 6 opposite the slot extends upwardly from the point opposite the slot so that every tendency is to minimize further travel of the 45 liquid particles even if there remain any appreciable velocity of the gas which rises from the wall. It will be evident further that as the gas is withdrawn through conduits 9 to the second drum which contains absorption means, a further expansion and reduction of velocity occurs in this 50 second drum. Thus, the absorption means are most favorably arranged.

The cross sectional area of flow being materially enlarged through the drum 6 and conduits 9, because of the great increase in cross sectional area of the conducting passageways, reduces the gas velocity so that it passes through the interstices of the adsorption material at such low velocity as to afford an enormous scrubbing action to effect separation of moisture particles from the gas. The adsorption material will absorb liquid from the gas so long as they are of 10 low percentage, or of such percentage that the surfaces of the material is never covered with a film of moisture. The action is such that the surface collects the liquids which, in turn, pass into the center of the adsorption material and 15 collect there as a liquid. When the mass of adsorption material is sufficiently saturated, the drops of liquid accumulate at the bottom of the adsorption chamber and fall by gravity through the apertures in the flanges 23 and the down 20 pipes 13' into the collecting drum 14. The choke 19 prevents by-passing of the gas from the drum 6 downwardly through the down pipes 12 and lower drum 13 across the pipe 17 and upwardly 25 through the drum 14 and down pipes 13'. The steam trap 18 effects the automatic removal of any condensates which collect in the transverse pipe 17.

Having thus fully described my said invention, what I claim as new, and desire to secure by Letters Patent, is—

A gas separator comprising a series of separator drums, two of the drums being upper drums disposed horizontally, the first of said drums containing a central distributor pipe slotted along 35 the bottom and at its center containing a gas inlet pipe, a gas conduit leading from the upper side of the first drum into the side of the second upper horizontal drum and a gas outlet pipe leading from the opposite side of the second 40 drum, an outlet at the bottom of the first drum, a gas scrubber interposed in the path of gas flow in the second drum, the gas scrubber having an inclined side to direct fluid downwardly to an outlet at the bottom of the second drum, there 45 being expansion space in the second drum between the gas inlet and the scrubber, and disposed below each of the upper horizontal drums respectively, gas expansion drums, each drum being connected to the outlet at the bottom of its respective upper drum, the bottoms of the lower drums being connected by a conduit, a liquid outlet opening from the conduit, there being a choke interposed in the said conduit to prevent circulation of gas around the system. 50 55
